UNITED STATES PATENT OFFICE.

THOMAS W. MORAN, OF BIRMINGHAM, ALABAMA, ASSIGNOR OF ONE-FOURTH TO
E. S. CURTIN.

ADVERTISING DISPLAY APPARATUS.

1,296,307

Specification of Letters Patent.

Patented Mar. 4, 1919.

Application filed November 13, 1918. Serial No. 262,364.

To all whom it may concern:

Be it known that I, THOMAS W. MORAN, a citizen of the United States of America, residing at Birmingham, in the county of Jefferson and State of Alabama, have invented certain new and useful Improvements in Advertising Display Apparatus, of which the following is a specification.

My invention relates to an advertising display apparatus, which is adapted to exhibit a plurality of signs arranged preferably in a polygonal frame which is movable so that they are intermittently changed in a novel manner.

One object of my invention is to mount the signs upon a rotatable rack or support which is suspended so that in addition to its rotation it will have a bodily movement toward and from the wall or supporting surface behind it, which bodily movement is in part responsive to gravity so that I obtain a more rapid change of the display and provide longer periods of rest for exposure of the different displays.

A further object is to provide a novel and simple drive for the display rack which will permit the latter to advance half of each shifting movement in response to a gravity action, leaving the mechanical drive to slowly follow up and again engage and move the display rack for the next change of display, this arrangement acting to double the duration of the stationary display periods as contrasted with the periods during which the apparatus is in motion.

My invention also comprises the novel details of construction of the display rack to the end that the latter may be produced in a very light form and inexpensively.

My invention further comprises the novel details of construction and arrangements of parts, which in their preferred embodiments only are illustrated in the accompanying drawings, and in which:—

Figure 1 is a longitudinal vertical sectional view through a street car showing a three sided display rack in front elevation and partially in section.

Fig. 2 is an end view of Fig. 1 with the wall broken away to show the rack in end elevation.

Fig. 3 is a sectional view on the line 3—3 of Fig. 1.

Fig. 4 is a view corresponding to Fig. 3 of a modified type of display rack. 55

Similar reference numerals refer to similar parts throughout the drawings.

As illustrated, the display rack is mounted upon a center shaft 1 which is preferably a light tube having fixed thereon by keys or equivalent means a plurality of spaced spiders having hubs 3 and radial arms 4. The spider is preferably made of thin light metal and at the outer end of each arm is provided a yoke bearing 5 for a light tie rod 6 which passes through suitable holes in the alining yokes of corresponding spider arms along the full length of the display rack. A light antifriction roller 7 is mounted to turn on the rod 6 as an axis in each yoke 5 70 and I mount on each rod 6 between adjacent spiders a U-shaped metal clip 8 having tongues 9 bent downwardly to form eyes through which the rod 6 passes freely, thus securing the clip thereon but leaving it free 75 to turn or rock. The edges of the clip overhang sufficiently to engage and hold the edges of advertising cards 10 when the latter are forced into place between the clips on adjacent spider arms in the manner shown 80 in Fig. 3. The rod 6, roller 7 and clips 8 are common to each spider arm so that the rack as thus assembled is adapted to have three display faces in which three longitudinal series of cards are detachably mounted. 85

The shaft 1 is journaled in the free ends of swinging arms or links 11 which are journaled on bearing brackets 12 made fast to the transverse end or vestibule walls of the car. The bearing bracket 12 is provided with a longitudinal bearing therethrough in alinement with a hole 13 in the vestibule wall 14 and a driving shaft 15 is passed through the hole 13 and through the bearing in bracket 12, and fast on its overhung inner end is a sprocket 16 which, by means of a sprocket chain 17, drives a sprocket 18 mounted free to rotate on the shaft 1. This sprocket 18 has on its side adjacent to the rack a lug 19 which is disposed to engage a shoulder 20 on an arm 4 of the adjacent spider and push it ahead of the lug, thereby 100

rotating the rack and its shaft 1. Washers 21 and 22 are disposed on each side of each link 11 and a key 23 holds the parts against endwise displacement from the shaft. A 5 worm wheel 24 is mounted on the outer end of the driving shaft 15 and is driven by a worm wheel 25 on a shaft 26 which is driven by a motor 27 attached to any suitable overhead support 28.

10 The driving mechanism shown is adapted to produce a very slow rotation of the display rack in a clockwise direction and as this rotation occurs the display rack will have an intermittent rotary and oscillatory 15 movement as follows: Assuming the lug 19 in engagement with the shoulder 20 and the spider in the position shown in Fig. 2, as the rotation of the lug takes place it pushes the rack ahead of it causing the 20 lower series of antifriction rollers 7 to ride up the wall 29 at the back of the display rack and swing the rack outwardly from the wall on its swinging arms 14 until the said series of alining rollers passes a dead 25 center position when the weight of the display frame will cause said rollers to snap forward and drop the rack back against the wall with the succeeding series of rollers in lowermost position. This gravitating movement of the rack relatively to its 30 driving sprocket is possible because the rack has no positive connection with the driving sprocket and is free at all times to move ahead of the pusher lug 19 on the sprocket.

35 The latter continues its slow follow up movement until it again picks up the shoulder 20 on the rack and then the shifting operation of the latter is repeated. In this manner the display rack has substantial 40 intervals of rest which are sufficient for display purposes and its bodily oscillatory movements serve to attract attention and at the same time maintain the rack normally in retracted position.

45 By reference to Fig. 4, I illustrate a spider having a hub 3^a and but two diametrically opposite arms 4^a, on one of which is provided the shoulder 20. The spider arms 4^a carry the yokes 5, rods 6, rollers 7 and clips 8, all as hereinbefore described, but to permit the display cards to be bowed slightly inwardly so as to insure their retention in the rack, I use a small diameter shaft 1^a and proportionately reduce the 50 diameter of the hubs 3^a so that the display cards can be mounted as shown in Fig. 4. The driving mechanism for the shaft 1^a is identical with that described for the shaft 1 and the operation of the display rack is 55 the same, except that it changes twice in each complete cycle of the driving lug 19 instead of three times and therefore has longer periods of rest equal each to a quarter of the time required for the rack's rotation.

While I have described and illustrated my display apparatus as applied to street cars, it will be understood that the rack may be designed and adapted for various and sundry display purposes.

This invention is not intended to be restricted in scope to the specific embodiments shown, but contemplates such modifications as come within the spirit and scope of the claims.

What I claim as new and desire to secure by Letters Patent, is:—

1. In a display mechanism, a rotary rack having a plurality of display surfaces, swinging supports for the rack and a rotatable pusher element to effect the intermittent rotation of said rack, and means to support the rack free for a gravitating movement.

2. In a display mechanism, a rotary rack having a plurality of display surfaces, swinging arms in which the rack is rotatably mounted free for a gravity controlled oscillatory movement, and a rotatable pusher element to effect the rotation and oscillation of said rack, said pusher element being supported at the free ends of said arms and having a driving element concentric with the arms, substantially as described.

3. In a display mechanism, a rotary rack having a plurality of display surfaces, swinging arms in which the rack is journaled, and a rotatable pusher element to effect the rotation and oscillation of said rack, said pusher element being supported at the free ends of said arms and having a driving element concentric with the arms, substantially as described.

4. In a display mechanism, a rotatable rack having a plurality of display faces, antifriction means at the junction of the outer edges of adjacent faces, a fixed support for the rack having swinging arms in which the rack is journaled, and a pusher means to intermittently rotate said rack and in conjunction with said support to effect the oscillatory movements of the rack.

5. In a display mechanism, a rack comprising a center shaft, a plurality of spiders thereon having antifriction rolls at their support engaging ends, a support for the rack having hinged arms in which the rack shaft is freely journaled, means to mount a plurality of display cards between each adjacent pairs of spiders, a sprocket rotatable on the shaft and having a lug, an element fast to the shaft and adapted to be engaged and pushed by said lug to rotate the rack, and means to rotate said sprocket, substantially as described.

6. In a display apparatus, a polygonal rack adapted to display a plurality of series of cards, antifriction elements at the apices of the rack, a supporting surface behind the rack adapted to be engaged by said elements,

swinging supports for the rack, and an intermittent drive to rotate the rack, substantially as described.

7. In a display apparatus, a polygonal rack adapted to display a plurality of longitudinal series of cards, rollers at the apices of the rack, swinging supports for the rack, and a rotatable pusher means to intermittently rotate the rack and the supporting

10 surface engaged by said antifriction means.

8. In a display rack, a shaft, a plurality of spiders fast thereon and having yokes at the free ends of the spider arms, longitudinal

rods mounted in the alining yokes on corresponding arms, rollers rotatably mounted 15 on the rods in position in said yokes, and display card clips mounted on the rods between adjacent spiders, swinging arms which support said rack, a fixed support engaged by said roller, and means to rotate 20 said shafts, substantially as described.

In testimony whereof I affix my signature.

THOMAS W. MORAN.
